UNITED STATES PATENT OFFICE.

JOHN S. MURPHEY, OF BALTIMORE, MARYLAND.

WATCH-BRACELET.

1,101,500.

Specification of Letters Patent. Patented June 23, 1914.

Application filed June 6, 1913. Serial No. 772,042.

To all whom it may concern:

Be it known that I, JOHN S. MURPHEY, a citizen of the United States, residing at Baltimore, in the State of Maryland, have invented certain new and useful Improvements in Watch-Bracelets, of which the following is a specification.

This invention relates to an improved construction of watch bracelet and has for its object to provide a simple and attractive holder to which chains or straps may be attached for attachment to the wrist of a wearer and which will securely retain the watch in place to prevent damage or loss while the watch is worn.

The invention is illustrated in the accompanying drawing, wherein,

Figure 1, shows a front face view of the improved holder and bracelet with a watch in place thereon. Fig. 2, illustrates the same as viewed in side elevation. Fig. 3, shows a rear view of the same with the watch in place in the holder. Fig. 4, illustrates the detached holder as viewed from the rear. Fig. 5, shows a side or edge view of the detached holder, and Fig. 6, illustrates a top plan or edge view of the holder.

Referring to the drawing the numeral, 7, designates a circular ring-band having a circular opening, 8, of substantially the size of the exposed face, 9, of a watch, 10. This ring-band comprises a comparatively narrow ring which is preferably concavo-convex in cross section to conform to the usually rounded circumference of the ordinary open-face watch case. At diametrically opposite edges the ring-band, 7, has spaced-apart rearwardly-extending bars, 11, which latter have bends, 12, therein and which are connected beyond the said bends by a cross-bar, 13. These bars, 11, and, 13, are formed integrally with the ring-band and by reason of their form a slot, 14, is produced so that a flexible band, strap or chain, 15, may be connected to the cross-bars, 13, and serve to attach the holder to the wrist. A lug, 16, extends rearwardly from the ring-band, 7, and projects in a plane between the spaced-apart bars, 11. The rear end of this lug, 16, curves downwardly so as to form clip and a slot, 17, extends cross-wise of the ring-band and also extends into the clip lug between the bars, 11. At the front side of the ring-band the slot, 17, communicates with the circular front opening at the upper edge of the watch face, 9. The rear edge of the

ring-band, 7, also has a plurality of rearwardly-extending clip lugs, 18, for engaging the rounded circumference of the watch case.

To attach the watch same is placed at the rear side of the holder and the ring, 19, stem, 20, and post, 21, of the watch are passed through the opening, 8, of the ring-band from the rear to the front, as shown in broken lines in Fig. 2, of the drawing. The post, 21, is then moved up into the slot, 17, of the ring-band and rearwardly extending lug, 16. The diametrically opposite side of the watch case is next pushed outwardly so as to seat the front side of the watch case against the inner side of the ring-band and during this movement the clip lugs, 18, will spring about the rim-edge of the watch case and hold the latter in the holder. When the watch is in place the ring-band, 7, will seat against the front side of the watch around the open face, 9, and the stem and post of the watch will have position in front of the upper cross-bar, 13, to which the wrist-engaging band is connected.

It will be noted that detachment of the watch case cannot take place by any outward movement because the ring-band seats against the outer face of the case and is viewed through the opening of the ring-band.

When the holder is attached to the wrist the rear side of the watch will be seated against the wrist consequently inward movement of the watch will be impossible during wearing, and as inward movement of the case alone can effect a detachment of the watch it is obvious that loss will be prevented as long as the ring-band is held in place by the flexible band or bracelet.

Having thus described my invention what I claim and desire to secure by Letters Patent is:—

1. A bracelet watch holder having a ring-band with a central opening and with watch-case engaging lugs projecting at one side thereof said band also having a watch-post embracing arm projecting at the same side as the said lugs with a slot extending from the central opening through the band and into the post embracing arm; means on the band adjacent to the slotted arm for engaging a bracelet end and means diametrically opposite the slotted arm for engaging another bracelet end.
2. A watch bracelet comprising a ring-

band with a view opening at the front side thereof of smaller diameter than the watch case to be received said ring-band having a lug extending rearwardly therefrom with a slot extending from the edge of the view opening rearwardly and into the said lug, said ring band also having a plurality of clip lugs on its rim edge and further provided with a bar at opposite sides of the slotted lug said bars being connected by a cross-bar, a bracelet having an end connected to said cross-bar and another bracelet-end engaging the ring-band at a point diametrically opposite the slotted lug.

15 3. A bracelet watch holder having a circular ring with a central view opening for a watch face said ring having watch-case

engaging lugs projecting at one side from its marginal edge; a watch post embracing arm also projecting from the marginal edge 20 of the ring and at the same side as said lugs said arm having a slot that is closed at the projecting end of the arm but which extends across the ring and opens into the central opening; a bracelet-engaging bar 25 formed on the ring at said slotted arm and another bracelet-engaging bar formed on the ring diametrically opposite said slotted arm.

In testimony whereof I affix my signature in presence of two witnesses.
